UNITED STATES PATENT OFFICE.

WILLIAM S. THOMAS, OF LOCK HAVEN, PENNSYLVANIA.

PROCESS FOR SECURING JACKETS ON ELECTRODE INSULATORS.

Application filed February 10, 1920. Serial No. 357,723.

To all whom it may concern:

Be it known that I, WILLIAM S. THOMAS, a citizen of the United States, residing at Lock Haven, in the county of Clinton and State of Pennsylvania, have invented certain new and useful Improvements in Processes for Securing Jackets on Electrode Insulators, of which the following is a specification.

10 Readily removable electrode insulators for spark plugs, such for example as used in internal combustion engines, are usually provided with metallic jackets for the purpose of taking the thrust of the clamping 15 gland nut when the latter is used to secure the electrode insulator to the body portion of the spark plug. It is quite obvious that the above mentioned metallic jackets are necessary for the purpose specified for 20 the reason that insulators are usually made of porcelain or other non-metallic material which is easily cracked and that it would not be practical to jam nuts or other binding portions directly against the porcelain insulator. However, it has long been a source 25 of trouble and a difficult problem to apply the metallic jackets to the porcelain insulators for the reason that if the jacket is clamped with sufficient pressure against 30 the porcelain insulator so as to prevent leakage of the products of combustion and also transverse current leakage there is a possibility that in securing the jacket to the porcelain insulator the insulator will be 35 cracked and thereby destroy the value of the insulator and render it either totally inoperative or cause the same to permit current leakage through the cracked portion of the insulator. Another of the past difficulties in jacketing porcelain insulators made 40 prior to my invention is that unless there is a possible chance for expansion of the insulator which necessarily occurs due to the extremely high temperature to which the insulator is subjected, the insulator is liable to 45 crack for the reason that it will jam against portions of the jacket which are unyieldable.

One object of my invention is to provide 50 an improved process whereby jackets of the above described type can be placed upon porcelain or other insulators in such manner that they will not cause the cracking of the insulator either during the application of 55 the jacket to the insulator or during the

use of the insulator as a part of a spark plug.

Another object is to so carry out my improved process that when the jacket is applied to an insulator an efficient seal will be 60 provided between the insulator and the jacket to prevent passage of oils or products of combustion therebetween and at the same time the insulator will be free to expand and contract within the jacket without causing cracking of the insulator or any detrimental effect to the insulator.

The insulators of the above type usually have an enlarged portion between their 70 ends; said enlarged portion being in the form of an annularly extending flange.

Another object of my invention is to so place a jacket upon an insulator of the above type that the jacket will be confined entirely to said flange and so that no portion of the 75 jacket will engage the insulator above or below said flange. Thus an insulator having a jacket placed thereon by my improved process will have said jacket secured to its strongest portion and not in contact with the portions of less diameter which would be more subject to fracture.

These objects, and other advantageous ends which will be described hereinafter, I attain in the following manner, reference 80 being had to the accompanying drawings in which—

Figures 1 to 8 inclusive are elevational views, partly in section showing various steps followed in carrying out my improved process of applying a jacket to an 85 electrode insulator.

Figure 9 is an elevation view of an insulator having a jacket secured thereon by my improved process, and

Figure 10 is an enlarged fragmentary view, partly in section, showing a jacket having been placed upon an electrode insulator by my improved process.

Referring to the drawings, 11 represents 100 a central sectional elevation of a base or primary die which at its top has a recess 12; the bottom of the recess forming a shoulder 13. A hole 14 extends through the body of the die 11 from the recess downwardly and 105 a flange 15 surrounds the recess. The top 16 below the flange 15 forms a ledge for a purpose hereinafter described. A metallic jacket 17, which is shown in central section in Figure 1, has a cylindrical portion 110

the same diameter as that of the recess 12 and is adapted to fit within the recess and rest upon the shoulder 13 as clearly shown in Figure 2. The jacket 17 is hollow in the 5 form of a collar and the flange 19 projects upwardly from the portion 18; said flange having its inner surface of the same diameter as the upper part of the inner surface of the cylindrical portion 18. However, the 10 flange 19 is of less external diameter than the external diameter of the cylindrical portion 18 so that a ledge 20 is provided. The extreme top portion of the flange 19 is beveled or chamfered inwardly as shown at 21. 15 The lower part of the inner surface of the cylindrical portion 18 is curved inwardly to a smaller diameter as shown at 22 and a hole 23 extends through the cylindrical portion 18; said hole being of less diameter than the 20 internal diameters of the cylindrical portion 18 and flange 19. Thus an inwardly projecting annular flange 24 is provided.

After placing the jacket 17 within the recess 12 as above described a ring washer 25 is inserted within the jacket as shown in 25 Figure 3. This ring washer is of less external diameter than the internal diameters of the flange 19 and upper part of the cylindrical portion 18 but is of greater external 30 diameter than the diameter of the hole 23. Thus the ring washer rests upon the curved surface 22 of the inwardly projecting annular flange 24.

An electrode insulator 26, which may be 35 made of porcelain, has an enlarged annular flange 27 between its ends 28 and 29. After the ring washer 25 has been inserted within the jacket as shown at Figure 3, the insulator is placed within the jacket so that the 40 lower surface of the flange 27 rests on the upwardly curved surface 30 of the ring washer 25 and the lower end 29 of the insulator extends through the ring washer 25, hole 23 of the jacket 17 and into the hole 14 45 of the base die 11. The flange 27 of the insulator is of less external diameter than the internal diameters of the upper part of the cylindrical portion 18 and flange 19 of the jacket 17. Thus there is a space 31 provided between the flange 27 and the jacket 50 17. After the insulator has thus been inserted as shown in Figure 4, a top die 32 is placed upon the base die 11; said top die having a cavity 33 into which the flange 15 55 of the base die 11 fits. An inwardly extending flange 34 of the top die 32 above the cavity 33 snugly fits around the flange 19 of the jacket 17 below its top and rests upon the ledge 20 of the jacket 17, as clearly 60 shown in Figure 5. Thus a hole 35 is produced by the flange 34 through which the flange 19 of the jacket 17 projects, and a recess 36 extends upwardly from the flange 34 to the upper surface of the top die 32. 65 With this construction it will be noted that the portion of the flange 19 of the jacket 17 above the flange 34 of the top die 32 extends into the recess 36 of the top die. After the top die has thus been placed, a second ring washer 37 is dropped over the end 28 of the 70 insulator 26 and this washer 37 has a downwardly curved surface 38 which fits against the top rounded edge 39 of the flange 27 of the insulator 26. The ring washer 37 is of less external diameter than the internal diameter of the flange 19 of the jacket 17 and the flange 27 of the insulator 26 is of such height or width that when thus positioned the ring washer 37 will be at a level below the top of the flange 19. The ring washers 80 25 and 37 are preferably made of a softer metal than that from which the jacket 17 is made, for example the jacket 17 may be made of steel and the ring washers 25 and 37 may be made of copper. 85

After the ring washer 37 has thus been placed, a primary plunger die 40 which has a sleeve portion 41 for encircling the upper end of the electrode insulator 26 is inserted within the recess 36. This plunger die 40 90 has an inwardly curved surface 42 which is of such diameter and curvature that when moved downwardly upon the chamfered upper edge 21 of the flange 19 as shown in Figure 6, the upper edge portion of the flange 19 will be turned over the top of the ring washer 37. However it is important here to note that the extreme edge portion 21 is not bent inwardly a sufficient distance to touch the insulator 26. In other words, as clearly shown in Figure 6, a space 43 exists between the edge 21 and the insulator 26. 95

After the upper edge portion of the jacket flange 17 has thus been turned, the primary plunger die 40 is removed from the recess 36 and a collar 44 is inserted within the recess 36 as clearly shown in Figure 7. This collar is of an internal diameter equal to the external diameter of the jacket flange 19 which has not been turned inwardly and the lower end of the collar 44 rests on the top of the flange 34. This collar 44 provides another recess 45 into which the lower sleeve end 46 of a secondary plunger die 47 is inserted. The lower end 48 of the secondary plunger die 47 is curved from a diameter less than the diameter of the hole formed by the turned-in edge 21 to a diameter greater than that of the hole formed by the turned-in edge 21 so that when the 100 die 47 moves inwardly the inner part 49 of the die will pass within the hole formed by said turned-in edge 21 of the jacket flange 19 and the remaining part of the curved surface 48 will bend the edge portion 21 of the 105 jacket downwardly to provide a hooked flange and at the same time will compress the ring washers 25 and 37 against the top and bottom rounded edges of the insulator flange 27 and the inner surface of the jacket. 110

115

120

125

130

It will be noted however that the part 49 of the secondary plunger die 47 will prevent any portion of the jacket flange 19 from engaging the insulator as is clearly shown in Figure 8. It will be further noted that by thus making a hooked flange at the top, the upper ring washer will be confined within the hooked flange and will only engage the insulator 26 at the top rounded edge 39. This latter action of the secondary plunger die 47 will also crush the lower ring washer 25 against the curved surface 22 of the collar and will be firmly lodged between said surface 22 and the lower rounded edge of the insulator flange 27. Thus the space 31 above described will be preserved between the ring washers 25 and 37 and the adjacent surfaces of the flange 27 and jacket 17. This space will permit expansion and also serve as an insulating space and by an inspection of Figure 10 it will be noted that any strain which is placed upon the insulator will occur directly against the enlarged and strong flange 27. Furthermore in view of the above described steps of my improved process, the pressure exerted by the ring washers 25 and 37 will be diagonally across the flange 27 and in this manner the weaker portions of the insulator will be free of any strains due to pressure exerted between the jacket, the ring washers and the insulator.

Having thus described my invention, what I claim as new and desire to secure by Letters Patent is:—

1. The process herein described which consists in providing an electrode insulator with an enlarged flange; placing the flange within a jacket; positioning a die to surround the jacket and engage with an edge portion thereof, and compressing the edge portion of the jacket inward and downward to form a hook-shaped flange adapted to

lock the jacket to the insulator flange but free from engagement with the body of the insulator.

2. The process herein described which consists in providing an electrode insulator with an enlarged flange; placing the flange within a jacket having an inwardly extending and an axially extending flange; positioning a die over and partly within the axially extending flange, and compressing said flange inward and downward in the form of an inner rolled edge adapted to lock the jacket to the insulator flange but free from contact with the body of the insulator.

3. The process herein described which consists of providing an electrode insulator with an enlarged flange between its ends; then providing a jacket having an inwardly extending flange and an axially extending flange; then inserting said insulator flange within the jacket; then compressing the edge of said axial flange simultaneously throughout its circumference in the direction of its length and toward the axis thereof to provide an inturned edge extending toward but spaced from the portion of the insulator at the outer side of said enlarged flange; and finally compressing said turned edge of the jacket inwardly over said enlarged flange of the insulator in the form of an inturned hooked flange and at the same time including means between the turned edge and said portion of the insulator whereby the hooked flange is kept from touching said portion of the insulator.

In testimony whereof I have signed my name to this specification in the presence of two subscribing witnesses.

WILLIAM S. THOMAS.
